E. B. HESS

TYPEWRITING MACHINE

Filed Sept. 21, 1921

UNITED STATES PATENT OFFICE.

EDWARD B. HESS, OF MANHATTAN BEACH, NEW YORK, ASSIGNOR TO ROYAL TYPE-WRITER COMPANY, INC., OF NEW YORK, N. Y., A CORPORATION OF NEW YORK.

TYPEWRITING MACHINE.

Application filed September 21, 1921. Serial No. 502,218.

To all whom it may concern:

Be it known that I, EDWARD B. Hess, a citizen of the United States, residing at Manhattan Beach, in the county of Kings, New York, and State of New York, have invented certain new and useful Improvements in Typewriting Machines, of which the following is a specification.

This invention relates particularly to type actions for typewriting machines, and especially to that class of type actions in which the type bars are actuated by the key levers through other levers interposed between the key levers and the type bars, and operatively connected therewith. In one form of such type actions, the interposed levers are in the form of bell cranks or two-arm levers and they are connected with the rear portions of the key levers and with the rear ends 20 or heels of the type bars, there being a slot and pin connection between some of the parts to permit of the proper movement of the type bars relatively to the key levers. My present improvements are preferably 25 applied to the kind of type actions in which the rear ends of the type bars are prolonged rearwardly beyond their pivots and slotted to receive pins carried by the interposed levers. Heretofore the operation of such 30 mechanism was such that when the key levers were depressed, the type bars were moved rapidly from positions of rest directly and without interruption to the printing point on the platen, and in such machines the type bars strike the platen with considerable force and objectionable noise is produced which by my invention is greatly decreased.

In my United States Patent No. 1,390,708 of Sept. 13, 1921, I have shown type actions in which provision is made for reducing the noise of the impact of the type bars on the platen and, therefore, I do not herein claim broadly type actions which are 45 so constructed as to reduce such noises, but according to my present invention, such broader invention is adapted to mechanism of somewhat different construction from that shown in my before mentioned patent.

In machines of the character before described, it is common to actuate the escapement mechanism directly by the type bars which operate directly upon the universal bar mechanism while the type arms are being moved rapidly toward the platen. Ac-

cording to one part of my present invention, the escapement is not operated during the initial movement of the type bars, nor while they are operating at high speed, but is operated during the latter part of the movement of the type bars during what is called in my prior patent "the momentum period", it being understood that the type bars are moved by a full depression of the keys to a point in advance of the platen, the further movement of the type bars to the platen being caused by the momentum of the type bars. The manner in which provision is made for reducing noise will be hereinafter more fully explained, but briefly stated the levers which are interposed between the key levers and the type bars are connected with the type bars by slot and pin connections and with the key levers by links or similar members in such manner that by the full depression of a key, the associated type bar is moved only to a position considerably in advance of the platen and the type bar is moved to the printing point by the momentum of the type bar, during which period the finger of the operator is usually on the key and the key makes a slight return movement which is resisted by the finger of the operator. When the key is further depressed, certain parts of the mechanism interposed between the key lever and the type bar assume a dead center or toggle locking position which is an important feature of the construction. My present invention involves also certain features of construction whereby the interposed levers are supported in a new way, and it also involves certain features of construction for supporting and operating the universal bar and escapement mechanism. These will be hereinafter explained.

In the accompanying drawings:—

Figure 1 is a view largely diagrammatic of portions of a typewriting machine embodying my improvements, some parts being shown in side elevation and some in section, and the position of some of the parts being slightly exaggerated for purposes of illustration.

Figure 2 is a detail view illustrating the connections between a key lever and a type bar. In this figure of the drawings, the parts are shown in dead center position when the pivot points at the opposite ends

of the link are in a straight line with the pivot of an interposed lever. This figure of the drawings also shows how the heel of a type bar makes contact with a universal bar at the commencement of the momentum period.

Figure 3 is a view similar to Figure 2 showing the position of the mechanism after the parts have passed dead center position 10 and it also shows that the universal bar mechanism has been moved rearwardly.

In Figure 1 of the drawings, parts of a typewriter carriage are indicated at A, and B indicates a platen. C indicates a type bar 15 segment and D, a type bar guide. Escapement mechanism is indicated at F, a key lever at G, and a type bar at H. The type bars normally lie horizontally, their rear ends being pivoted to the segment at c and 20 their front ends being supported by a cushioned rest I. The rear ends of the key levers are pivoted at i to a support J and the upward movement of the front portions of the key levers is arrested by a cushioned 25 stop K.

Each type bar H is formed with a rearwardly extending, downwardly inclined slotted arm h which is connected to a lever L by a slot and pin connection.

30 Each lever L is pivotally mounted on a stationary support M, and each of these levers comprises a short arm extending forwardly from its pivot and a long arm extending upwardly and rearwardly from its pivot. A frame N is pivotally connected at m with the support M and its position may be adjusted on the support by an adjusting screw O. Each lever L is pulled rearwardly above its pivot by a spring n attached to 35 the frame N and each key lever G is connected with the frame N by a spring g. By means of the set screw O which adjusts the frame N, the tension of the springs n and g may be simultaneously varied.

40 The short arm of each lever L is connected by a link P with an associated key lever. The connections at y, y' are pivotal to allow the necessary freedom of movement.

45 Normally the key levers and type bars lie in a substantially horizontal position and are practically parallel with each other and at this time the links P are inclined rearwardly as shown in Figure 1. When in normal position, the connections between the links P and the levers L are such that when the keys are depressed, a direct pull is effected on the levers which rapidly moves them, their upper ends being swung forward and by means of the slot and pin connection described and clearly shown in the drawings, each lever is moved by the full depression of an associated key to the position shown in dotted lines at X, Figure 1.

50 At this time, the pin on the lever L is near the inner end of the slot in the heel of the

type bar, as shown in Figure 2, and also by dotted lines in Figure 1. This is the full movement given to the type bar by the associated key, but the momentum of the type bar carries it to the printing point indicated at Z in Figure 1. In this way the noise of the impact is greatly reduced and blurring of the print is prevented. It will be observed by reference to Figure 3, that during the momentum period the pin of the lever L moves outwardly in the slotted arm of the type bar, and it will be observed in Figure 3 that the pivot points l, y and y' have been moved from their dead center position.

55 The escapement mechanism F is similar to that employed in the Royal standard machine. A slight modification is shown at U. The device there shown is for the purpose of restoring the rocker plate to position. It comprises a screw u operating in a tapped opening in the escapement frame U' and having a reduced portion u' extending through the rocker plate u². The front end of the part u' carries a collar u³ and another collar u⁴ is carried by the part u' next the rocker plate. A spring u⁵ is interposed between the two collars. At its rear end, the screw u' carries a lock nut u⁶. By means of the screw the tension of the spring u⁵ may be varied. The spring serves to restore the rocker plate to position after its operation. The rocker plate carries a spring arm f' equipped with a roller f and the position of the roller f on the rocker plate may be adjusted by a screw f².

60 The universal bar mechanism comprises a frame Q carrying at its front end a semi-circular member q and a guide finger q' which extends through the segment C. This frame is supported by an arm s which is pivotally connected with the frame at s' and it is connected to an arm V rigidly secured to a stationary rod S. This arm carries an eccentric s² which is adjustable and the outer end of the arm V is connected with the arm s by a spring s³. By these devices the relation of the universal bar mechanism to the escapement mechanism may be adjusted. The frame Q has a downwardly extending arm r which makes contact with the roller f of the escapement. This contact is maintained at all times and the arm is of sufficient length to permit the carriage with the escapement mechanism to be raised and lowered for case printing, contact between the roller f and the arm r being maintained at all times.

65 The relation of the universal bar mechanism with the type bars and with the escapement mechanism is such that while the universal bar mechanism is in contact with the escapement mechanism at all times, the type bars are normally out of contact with the universal bar, but their cammed por-

tions h' make contact with the universal bar at the commencement of the momentum period and actuate the universal bar only during the momentum period. The cam surfaces of the type bars come gradually into contact with the universal bar and inasmuch as the universal bar is always in contact with the escapement mechanism, a source of noise incident to other constructions is 10 eliminated.

I claim as my invention:

1. In a typewriting machine, the combination with the key levers and the type bars, of connections interposed between the rear portions of the key levers and the rear portions of the type bars, said connections each comprising a sub-lever operatively connected with a rearwardly extending portion of the type bar, said sublever being mounted to 20 move about an axis in the rear of the type bar pivot and having a toggle link connection with the rear portion of a key lever which is moved into toggle locking connection by the full depression of a key lever, the 25 type bar then being at a distance from the platen and completing its movement by its own momentum.

2. In a typewriting machine, the combination with the key levers and the type bars, 30 of connections between the key levers and the type bars, said connections each comprising a lever pivotally mounted in the rear of the type bar pivot and having pin and slot connection with a type bar and a link connection with the key lever, the parts being arranged so that a full depression of the key lever causes a dead center relation therebetween with the type bar at a distance from the platen from which it completes 35 its travel by its own momentum, thereby reducing noise.

3. In a typewriting machine, the combination with the key levers and the type bars, 40 of two armed levers mounted in the rear of and below the type bar pivots, each of said levers having a long arm with a pin and slot connection with its type bar in the rear of the type bar pivot, and a shorter arm having a link connection with its key lever, 45 a full depression of the key moving the link connection into a dead center position with the type bar at a distance from the platen from which it completes its travel by its own momentum, thereby reducing noise.

55 4. In a typewriting machine, the combination with the key levers and the type bars, of two-armed levers mounted in the rear of the type bar pivots, each lever having a long arm with a pin and slot connection 50 with its type bar, and an arm having a link connection with the key lever, a full depression of the key lever moving the parts to a position in which the ends of the link and the pivot of the two-armed lever lie in a 60 straight line while the type bar is at a dis-

tance from the platen from which it completes its travel by its own momentum, thereby reducing noise.

5. In a typewriting machine, the combination with the key levers and the type bars, 70 of interposed sub-levers, springs for returning the key levers to normal position, springs for returning the sub-levers to normal position, and means for simultaneously adjusting both series of springs. 75

6. In a typewriting machine, the combination with the key levers and the type bars, of two-armed levers having link connections with the key levers and slot and pin connections with the type bars, a support 80 for said two-armed levers, a frame pivotally connected with said support, means for adjusting the frame on said support, and springs connecting the frame with the key levers and with the two-armed levers. 85

7. In a typewriting machine, the combination with the key levers and the type bars, of connections comprising interposed levers, a support for said interposed levers, springs for returning the interposed levers to normal position, springs for returning the key levers to normal position, and means adjustably mounted on said support for simultaneously adjusting both series of springs. 90

8. In a typewriting machine, the combination of a universal bar, means for supporting the same for movement about a fixed pivot, escapement mechanism with which said universal bar has constant engagement, a stationary member independent of said supporting means, and an eccentric carried thereby and engaging the bar supporting means, the adjustment of said eccentric varying the position of the universal bar relatively to the escapement mechanism. 100 105

9. In a typewriting machine, the combination of type bars, a universal bar operated by the heels of the type bars, a support for said universal bar, escapement mechanism with which the universal bar has constant 110 engagement, a stationary member independent of said supporting means, and an eccentric carried thereby and adjustable to vary the position of the universal bar relatively to the heels of the type bars and to the escapement mechanism. 115

10. In a typewriting machine, the combination with the key levers and the type bars, of connections between the key levers and the type bars, said connections each comprising a lever pivotally mounted in the rear of the type bar pivot and having pin and slot connection with a type bar and a link connection with the key lever, the parts being arranged so that a full depression of the key lever causes a dead center relation therebetween with the type bar at a distance from the platen, escapement mechanism, and universal bar mechanism engaged by the type bars only when the parts have reached said 120 125 130

dead center relation and operated by the type bars during their momentum movement to printing position.

11. In a typewriting machine, the combination with the key levers and the type bars, of two-armed levers mounted in the rear of the type bar pivots, each lever having a long arm with a pin and slot connection with its type bar and an arm having a link connection with the key lever, a full depression of the key lever moving the parts to a position in which the ends of the link and the pivot of two armed lever lie in a straight line with the type bar at a distance from the plate, escapement mechanism, and universal bar mechanism operating the same and engaged by the type bars only at the end of a full depression of the key lever and operating the escapement mechanism during the momentum movement of the type bars.

12. In a typewriting machine, the combination with the key levers and the type bars, of levers interposed between the rear portions of the key levers and the rear portions of the type bars which are operatively connected with the type bars and have linked connections with the key levers in front of their pivots, the points of connection of each lever and link being so related to the type bar and key lever that a full depression of the key lever causes the type bar to move a considerable distance from the platen and to complete its movement by its own momentum.

13. In a typewriting machine, the combination with the key levers and the type bars, both of which lie in horizontal planes, of substantially vertical connections interposed between the type bars and the key levers, said connections each including a sub-lever mounted to turn about an axis in the rear of the type bar pivot and having one arm

operatively connected to the type bar, and a toggle link connection between the sub-lever and the key lever which is moved into toggle locking position by the full depression of a key lever, the type bar then being at a distance from the platen and completing its movement by its own momentum.

14. In a typewriting machine, the combination with the key levers and the type bars, both of which lie in substantially horizontal planes, of intermediate connections which lie in a substantially vertical plane and each of which comprises a sub-lever pivotally mounted in the rear of the type bar pivot and having its longer arm connected to a rearwardly extending portion of the type bar, and a toggle link which connects the sub-lever and key lever and is moved into toggle locking relation thereto by a full depression of the key lever, the type bar then being at a distance from the platen and completing its movement by its own momentum.

15. In a visible writing machine, the combination with key levers whose free ends are toward the front of the machine and type bars whose free ends lie toward the front of the machine, of intermediate connections comprising a two-armed lever, a pin and slot connection between the long arm of the two-armed lever and the heel of the type bar and a link operatively connecting the short arm of the two-armed lever and the key lever intermediate its length, a full depression of the key lever moving the parts to a position in which the link and the pivot of the two-armed lever lie in a straight line, the type bar then being at a distance from the platen and completing its movement by its own momentum.

In testimony whereof, I have hereunto subscribed my name.

EDWARD B. HESS.
